UNITED STATES PATENT OFFICE.

JOHN W. GRAHAM, OF HINTON, WEST VIRGINIA.

TYPOGRAPHICAL OR LINE-CASTING MACHINE.

1,229,605.

Specification of Letters Patent. Patented June 12, 1917.

Application filed May 12, 1915. Serial No. 27,607.

To all whom it may concern:

Be it known that I, JOHN W. GRAHAM, a citizen of the United States, residing at Hinton, in the county of Summers and State 5 of West Virginia, have invented certain new and useful Improvements in Typographical or Line-Casting Machines, of which the following is a specification.

My invention relates to typographical or 10 linecasting machines, such as linotypes of the original construction; wherein circulating matrices are released from a magazine in the order in which their characters are to appear in print, and then assembled in line 15 together with expanding spacers, the composed line brought in contact with the face of a mold, the mold filled with molten metal to form a line of type or slug against the matrices, which produce the type characters 20 thereon, and the matrices thereafter returned to the magazines from which they were originally drawn.

More particularly it relates to that class 25 of machines, having a series of magazines, any one of which can be brought into operative position, and wherein the magazines are removable and interchangeable, and to that end are mounted on a spider or rack, such spider or rack being mounted upon a 30 shaft, housed at the front and rear on bearings affixed to the frame of the machine, to allow the magazines to revolve into exact operative position.

In the drawings I have shown my invention 35 as applied to a linotype machine, but, obviously, it may be applied to other machines such as typesetters and typecasters, and many changes and variations could be made therein without departing from the 40 spirit, or principle of this invention.

Referring to the drawings Figure 1 is a side view of a portion of a linotype machine having my invention applied thereto. Fig. 2 is a front view of the main arm of the machine, showing the casting which houses the bearing at the front, and part of the casting at the back which supports the rear bearing. This view also shows a magazine in the rack, in operative position. Fig. 3 is a side view 45 of a section of magazine with a verge in place, and the trip finger which trips the verge. Fig. 4 shows the locking device. Fig. 5 is a view of the rack or spider. Fig. 6 is a side view of a section of an angle iron 50 upon which the magazine rests, showing the slots to engage the extended ends, of the

strengthening bar. Fig. 7 is a fragmentary plan view of a part of a magazine with its strengthening bar. Fig. 8 is a perspective view of a section of a magazine showing the 60 projecting end of the strengthening bar, which is designed to engage the slot in the angle iron side, of the basket.

Referring to Fig. 1:

A is the main arm of the machine.

65

A¹ is a cross arm bolted or otherwise securely affixed to the main arm A.

A² represents the forked arm which supports the shaft G at its frontal end.

A³ is an arm already on all machines of 70 the class described, and from which is extended the supporting arm A².

A⁴ shows magazines mounted in place on rack H.

Referring to Fig. 3:

75

V represents a verge in place, holding matrix V¹ in place.

V² represents a trip finger.

V³ represents a slotted key rod.

V⁴ represents a pin, on which the finger 80 V² is pivoted.

V⁵ represents a spring, to hold the finger V² in place.

V⁶ represents a spring, to hold the verge 85 V in place.

V⁷ represents a casting, in which the finger V² is housed.

Referring to Fig. 4:

P shows the lock pin housed in the casting V⁷.

90

In operating the machine the pin P shown in Fig. 4 is withdrawn and the desired magazine turned to operative position. The pin P is then allowed to enter socket, in the magazine, thus locking the 95 magazine in place. This socket is a hole in the bar which houses the verges, and the hole is so placed near the end of the bar that when the pin P is socketed in said hole the magazine is in operative position. Each of 100 the magazines is made with a like hole or socket. To remove the magazine from the rack or spider, which is herein shown in the form of a truncated triangular pyramid, the magazine is moved back in its wedge shaped 105 support a distance, sufficient to allow the extended ends of the strengthening bars H⁴ to become disengaged from the slots H³ in the rack bars H². The magazine is then lifted up to allow these projections H⁴ to 110 pass over the top of the angle irons H² and allow the magazine to be removed.

The verge V shown in Fig. 3 is so constructed as to hold the outmost matrix in place with its front pawl, its rear pawl rising up between the ears of the next matrix, 5 when the escapement mechanism is tripped. The verge V is tripped by the trip finger V², which is housed in a slot in the casting V⁷, and the spring V⁶ also rests in the said slot in the casting V⁷. The finger V² is connected to the key rod V³, by the pin V⁸, and the said key rod V³ is slotted vertically where it connects with the pin V⁸.

Having described my invention, its construction and operation, what I claim and 15 desire to secure by Letters Patent of the United States, is as follows:

1. In a typographical machine the combination of a plurality of removable magazines, housed on a spider or rack, said rack made in the general form of a truncated, triangular pyramid, and means whereby said rack may be rotated to bring the magazine into operative position.

2. In a typographical machine the combination of a plurality of removable magazines, a spider or rack in which said magazines are housed, said rack made in the general form of a truncated, triangular pyramid, a shaft permitting rotation of said rack, bearings affixed to the frame of the machine, 25 one at the front and one at the back, supporting said shaft, whereby the spider or rack can be revolved to bring any desired magazine into operative position.

3. In a typographical machine the combination of a plurality of removable magazines having projecting strengthening bars, a spider or rack in which said magazines are housed constructed in the general form of a 30 truncated, triangular pyramid, angle iron rests supporting said magazines, having slots to engage the projecting ends of said strengthening bars of the magazines, adapted to hold said magazines in place, both horizontally and vertically.

4. In a typographical machine the combination of a plurality of removable magazines, a rotatable rack to house said magazines being made in substantially the form 45 of a truncated polyhedron, a centrally and

longitudinally disposed shaft upon and about which said rack is adapted to turn, and rack bars attached to the said rack to hold the magazines in place.

5. In a typographical machine the combination of a plurality of removable magazines, a rack to house said magazines being made in substantially the form of a truncated triangular pyramid, and rack bars attached to said rack to hold the magazines in 55 place having slots therein to be engaged by said magazines.

6. In a typographical machine the combination of a plurality of removable magazines, a rack to house said magazines being 60 made in substantially the form of a truncated triangular pyramid, rack bars attached to the said rack adapted to hold the magazines in place, having slots therein and bars attached to the said magazines having projecting ends to engage slots in said rack bars.

7. In a typographical machine the combination of a plurality of removable magazines, a rack in the form of a truncated triangular pyramid to house said magazines 75 and a shaft extending centrally through the said rack permitting rotation of said rack.

8. In a typographical machine the combination of a plurality of removable magazines, a rotatable rack in the form of a truncated pyramid to house the said magazines, a shaft extending centrally and longitudinally through the said rack, and bearings to support said shaft.

9. In a typographical machine the combination of a plurality of removable magazines, a rotatable rack to house the said magazines, said rack being made in the form of a truncated pyramid, a shaft extending centrally and longitudinally through said 80 rack, bearings to support said shaft and a supporting frame affixed to the frame of the machine to support the said bearings.

In testimony whereof I affix my signature in presence of two witnesses.

JOHN W. GRAHAM.
